UNITED STATES PATENT OFFICE.

STEPHEN T. WILLIAMS, OF NEW YORK, N. Y.

CARD-RECORD.

SPECIFICATION forming part of Letters Patent No. 624,597, dated May 9, 1899.

Application filed October 25, 1898. Serial No. 694,520. (No model.)

To all whom it may concern:

Be it known that I, STEPHEN T. WILLIAMS, a citizen of the United States, and a resident of the borough of Manhattan, in the city of 5 New York and State of New York, have invented a new and useful Improvement in Card-Records, of which the following is a specification.

In the tab-card system of indexing or recording on cards filed in a drawer or box the cards when in place are usually distinguished each from the other by what may be termed and will be hereinafter referred to as "index characters," and which may be letters, numerals, or other characters or words printed or written on one side only of portions of the cards projecting from their upper edges and called "tabs." A complete set or series of these cards may and usually will consist of 20 several groups, each group comprising a certain number of cards numbered or in any way indexed consecutively to form one complete index.

It is frequently the case that both sides of 25 a card are required for records. In that case the card when removed from its group must be turned over by the hand, and after the records have been made it must be turned back again in order that the index character may 30 face the recorder or searcher. If the card have only a single tab inscribed on the back with the same index character as that upon the front of the tab, whenever the card is reversed as to face and back, but without reversing 35 top and bottom, the tab will occupy a different position in the index order from its former one and disconcert the searcher. This dis-arrangement of index order by such reversal of a card is unavoidable with any card group 40 or series bearing but one index of consecutive letters or numbers. If every card of such a group is reversed whenever the consecutive order of the index characters on the back of the card is consulted, the card must be taken 45 from its place and turned over for inspection and turned back again when restored to its place in the file. The motions involved in this taking out and turning over consume time, and when many hundreds or thousands 50 of cards are to be handled in a day, whether by one person or many, the wasted time and energy become a very sensible quantity. An

attempt to remedy this fault has been made in which the backs of the cards are so ruled that records on the back begin at the bottom 55 of the card and proceed upward, the intention being to enable inspectors to read the backs as well as the fronts without removal from the file. Practically the plan is a failure, the inspector being obliged to bend his 60 body or neck into unnatural positions to read the back of the card at all and obscuring the light necessary for rendering the records legible in a card-file. Again, with all tab-card indexes or records heretofore used in 65 drawer or box files only the person in front of or facing the file could conveniently read the index characters and use the file at one time.

This invention has for its object, first, the 70 saving of wasted motions and time in reading and handling such card-indexes or record-cards, and, second, providing for or facilitating the filing and inspection of such card-records, &c., by two or more persons at the same 75 time.

I effect my purpose by providing two index-tabs upon the same edge of each card in a group, these tabs, which I term "twin" tabs, 80 being in the same relative position measured from the two ends or two opposite edges of the card and so positioned that upon reversal of the card side for side and back for front the twin tabs exchange places in the index order. I indite the same index character 85 upon the face of one tab and upon the back of its twin tab preferably in inks of different colors for the front and back of the two tabs. My object in using different-colored inks for 90 this purpose is to have the changed color inform the inspector that the card has been reversed and that there are records on the reverse side. Otherwise the inspector who wishes to know how much matter has been recorded and if the reverse side has been used 95 must remove the card from its file and turn it over to ascertain the information.

To more fully explain the invention, I have 100 illustrated it by drawings, in which—

Figure 1 is a perspective view of a box or 100 drawer containing the three groups of cards having my twin tabs. Fig. 2 is a perspective view of a single group of such cards separated a little way apart to illustrate more

clearly what I call the "twin-tab" system. Figs. 3 and 4 are respectively front and back views of the same one of the cards shown in Fig. 2. Figs. 5 and 6 are respectively front views of a card, illustrating a modification. Fig. 7 is a perspective view of a group of cards, illustrating another modification of my invention.

Similar letters of reference designate corresponding parts in all the figures.

Referring first to Figs. 1, 2, 3, and 4, in which *a a* are cards, each having on its upper edge the pair of tabs *b b'*, which I call the "twin" tabs, equidistant one from one side edge and the other from the other side edge of the card. Ten of these cards constitute a group. The upper edge of each card may be considered as divided into twenty spaces, from two of which project the twin tabs, which on 15 the front card of a group are in the spaces next the side edges and have inscribed on them the numerals "1 1" and on the next card are in the next spaces and have inscribed upon them the numerals "2 2," and so on to the tenth spaces, which are inscribed with "0 0." The said numerals from "1" to "0," counting from one side edge, are on one side of the card, which may be considered as the face, and those counting from the other side edge 20 are on the other side of the card, which may be considered as the back, as may be understood by reference to Figs. 1 and 2, wherein the numerals counting from the left are represented in full outline and those counting 25 from the right in dotted outline and reversed as though seen through the card. The faces of the tabs or the numerals thereon should be distinguished from the backs of the tabs or the numerals thereon in some way—as, for 30 example, the numerals on the face and back may be of different color, as may be understood by reference to Figs. 3 and 4, the tabs being of the same color as the body of the card on both sides, or the faces of the tabs 35 may be of one color and the backs of another color, as may be understood by the shading of the tabs in Figs. 5 and 6, the numerals being of the same color on both sides of the card.

The different groups in a series may be distinguished one from the other by different colors of the tabs regardless of the similarity or dissimilarity of the index colors on the two sides of the tabs, as may be understood by reference to Fig. 1, where the tabs of the 45 three series are differently shaded to indicate differences of color. While I preferably apply this indexing to the upper edge of the card, I may apply it to one of the side edges, as illustrated in Fig. 7. In that case the box 50 or drawer in which the cards are filed should be of skeleton form or open at one side to permit viewing the index and the withdrawal and replacement of the cards in a lateral direction.

65 It is plain that in one complete group of my twin-tab system having every tab indexed as described such group will contain dupli-

cate indexes upon a single edge, one complete index reading from the front of the file and the other complete index reading from the 70 back of the file at the same time. In this system no two tabs in a complete consecutive-index group will lie one behind the other; but every index character on its face or on its back may be read at the same time by 75 persons placed in front or at the back of the drawer or other receptacle containing the filed cards.

A complete group in my system is thus seen to possess duplicate indices upon one edge 80 instead of a single index, as in the old system. A complete group of my cards presents the same consecutive-index characters whether viewed from the back or front.

In practice when the face of a card of my 85 system has been filled by records and the back of the card is required for additional records the original position of the card is reversed side for side and back for face, the right-hand twin tab thus exchanging place 90 with that on the left and presenting to the inspector at the front of the file a duplicate of the index character shown on the former tab in its proper index order. The changed color of the index character notifies the inspector 95 of reversal of the card. The records last made on the card are thus at once seen by the inspector at the front without the necessity of removing the card from its file and turning it over. The index order is not disturbed, and the index characters can still be read in their proper order from the rear, as before.

In the old and single-tab system if the index-tab should have the same index character inscribed upon its back the card could 105 not be so reversed, because its tab would fall out of its proper indexed order and confuse the filer and searcher.

It is obvious that the twin-tab system of 110 indexing is not confined to the decimal numeration of the indices, but that the indexing may be by the days of the week or the months or the letters of the alphabet and, in fact, by any index character that may be suitable, according to the nature of the record 115 which is to be kept.

What I claim as my invention is—

1. In a group of index or record cards or sheets consecutively indexed in opposite directions, twin index-tabs provided upon one edge of each of such cards or sheets, so positioned that by reversal of a card side for side and back for front, the twin tabs are caused to exchange places in the index order, substantially as and for the purpose herein described.

2. A group of index or record cards each having upon one edge two tabs with the same index character inscribed upon one side of one of said tabs and upon the opposite side of the other one, substantially as and for the purpose herein described.

3. A reversible index-card having on one

edge two index-tabs bearing one on its face and the other on its back corresponding index-signs and having the faces of the index-tabs distinguished from the backs thereof by 5 different colors, substantially as and for the purpose set forth.

4. A reversible index-card having on one edge two index-tabs bearing one on its face and the other on its back corresponding index-signs which are of one color on the face 10

and another color on the back of the card, substantially as and for the purpose set forth.

In testimony that I claim the foregoing as my invention I have signed my name, in presence of two witnesses, this 21st day of October, 1898.

STEPHEN T. WILLIAMS.
